UNITED STATES PATENT OFFICE.

HARRY M. PFLAGER, OF ST. LOUIS, MISSOURI, ASSIGNOR TO COMMONWEALTH STEEL COMPANY, OF ST. LOUIS, MISSOURI, A CORPORATION OF NEW JERSEY.

LOCOMOTIVE BED.

Application filed December 1, 1924. Serial No. 753,277.

To all whom it may concern:

Be it known that I, HARRY M. PFLAGER, a citizen of the United States, residing at St. Louis, Missouri, have invented a certain new and useful Improvement in Locomotive Beds, of which the following is a specification, such as will enable others skilled in the art to which it appertains to make and use the same.

10 My invention relates to railway rolling stock and consists in an improved locomotive bed construction of the type adapted for locomotives utilizing trailer trucks and having a cradle at the rear of the side frames 15 which is supported by the trailer truck.

In a prior Patent, No. 1,174,272, issued to me March 7, 1916, I show a locomotive bed formed of a one-piece casting and my present invention utilizes this unitary construction for a bed of the type referred to, and the objects of my invention are to form integral with the side frames of the locomotive, cradle members, steam cylinders and steam cylinder supply chambers, guide 25 yokes, a deck plate with drawbar pocket, an air brake cylinder bracket, trailer truck center and side bearings, and boiler support elements either acting directly or used in connection with expansion plates. By thus 30 combining many locomotive parts, I provide a rigid structure in which the relative positions of different operating members on the locomotive are fixed and the distances between them are not subject to as great variations in the original structure as are 35 likely to be caused by an assembled construction, and I also avoid play at different points due to loosening of the fastening elements used in an assembled structure. In various 40 places where the clearance between bed and other locomotive parts is slight, the integral construction permits the use of heavier elements or parts shaped better for the purpose intended and such structure also eliminates 45 the difficulty encountered in attempting to assemble separate members in inconveniently narrow places.

In the accompanying drawings which illustrate my invention—

50 Figure 1 is a top view of the longitudinal half of a locomotive bed embodying my invention.

Figure 2 is a side elevation of the same.

55 Figure 3 is a vertical transverse section on line 3—3 of Figure 1.

Figure 4 is a vertical transverse section on line 4—4 of Figure 2.

Figure 5 is a similar section illustrating a modified construction.

Figures 6 and 7 are vertical longitudinal 60 sections taken on lines 6—6 and 7—7, respectively, of Figure 1.

Figure 8 is a vertical transverse section taken on line 8—8 of Figure 2.

Figures 9 and 10 are vertical transverse 65 sections taken on lines 9—9 and 10—10, respectively, of Figure 1.

The locomotive bed comprises side frames 1 integrally connected at various points by cross members 2 and provided with driving 70 box pedestals 3. Extending rearwardly of the rear pedestals 3 are integral cradle forming members 4 united at their rear ends by a transverse member 5 forming a deck plate and provided with a drawbar pocket 6. Extending outwardly from cradle 4 adjacent to the deck plate is an integral arm 7 provided with side bearings 8 for engaging the trailer truck, which is not shown. The deck 75 plate and arm are provided with expansion 80 plate bearings 9 and the forward end of the cradle has integral sliding boiler supports 10. The forward ends of the cradle members are provided with suitable projections 85 11 forming brake hanger lugs. Intermediate the cradle and trailer truck side bearings the cradle member 4 is provided with an integral bracket 20 for mounting an air cylinder.

At the end of the side frames opposite to 90 the cradle members are the steam cylinders 12 which are cast with the side frames and preferably formed integrally with the steam cylinders are the steam supply chambers or steam chests 13 which are also integrally 95 united with the bed and the boiler support 14. Spaced from the steam cylinder but formed integrally with the side frame is the guide yoke 15.

The forward ends of the cradle members 100 at the rear of the side frames are connected by a cross member 16 the lower portion of which forms a center bearing 16* upon which may be pivoted the forward end of the trailer truck frame.

In the construction shown in Figure 5, the steam cylinder 17 is supplied through a piston valve 18 which is integral with the bed 19 but is not integrally united with the steam chest. Obviously, the steam supply member 110

could be formed separately from the bed and steam cylinder and applied thereto in the usual manner without departing from that part of my invention which includes an integral construction of the steam cylinder and locomotive bed.

Various other modifications, such as the elimination of one or more of the particular elements mentioned as forming part of the locomotive bed casting, will suggest themselves to those familiar with the art and I include such modifications within the scope of my invention as claimed.

With the use of my invention in its preferred form, the entire bed is formed of a one-piece casting and the likelihood of variations in positioning the wheels, pistons, connecting rods, brakes, side bearings, etc., is reduced to a minimum and when the locomotive is once assembled, the likelihood of these parts being thrown out of alignment or other proper relative position is also minimized. These advantageous features are in addition to the advantages of better distribution of material and reduction in the original expense of producing a complete locomotive.

I claim:

1. A locomotive bed comprising side frames, and a cradle extending rearwardly from said side frames and formed integrally therewith.
2. A locomotive bed comprising side frames including driving box pedestals, and an integral cradle extending rearwardly from said side frames and including integral side bearings for a trailer truck.
3. A locomotive bed comprising integral side frames, cradle, and center and side bearings for a trailer truck.
4. A locomotive bed comprising side frames including driving box pedestals, and cradle forming members extending rearwardly from the lower portions of the rear pedestals and formed integrally therewith.
5. A locomotive bed comprising integral side frames, cradle forming members, and cross members uniting the rear ends of said members to form a deck plate.
6. A locomotive bed comprising integral side frames, cradle forming members, and cross members uniting the rear ends of said members to form a deck plate and provided with a drawbar pocket.
7. A locomotive bed comprising integral

side frames, cradle members, cross members between the side frames and between the cradle members, and sliding boiler support and expansion plate bearings on said cross members.

8. A locomotive bed comprising integral side frames provided with driving box pedestals, a cradle provided with side bearings for the trailer truck and with brake hanger lugs.

9. A locomotive bed comprising side frames provided with an integral boiler support at their forward ends and with an integral cradle at their rear ends.

10. A locomotive bed comprising side frames provided with integral steam cylinders at their forward ends and with integral cradle forming members at their rear ends.

11. A locomotive bed comprising side frames and integral steam cylinders.

12. A locomotive bed comprising side frames and integral steam supply chambers.

13. A locomotive bed comprising side frames and integral steam cylinders and steam supply chambers.

14. A one-piece casting forming a locomotive bed with integral boiler support steam cylinders and steam supply chambers.

15. In a locomotive bed, integral side frames, steam cylinders, driving box pedestals, a cradle, and trailer truck bearings.

16. A locomotive frame having a guide yoke formed integrally therewith.

17. A locomotive frame having a steam cylinder and a guide yoke formed integrally therewith.

18. A locomotive frame having driving box pedestals and a guide yoke formed integrally therewith.

19. A locomotive side frame having driving box pedestals, a guide yoke, and steam cylinders formed integrally therewith.

20. In a locomotive frame, a cradle and an integral air cylinder bracket formed on the side of said cradle.

21. A locomotive unitary structure comprising a cradle with an air cylinder bracket and a brake hanger lug cast integrally with said cradle.

In testimony whereof I hereunto affix my signature this 25 day of November, 1924.

H. M. PFLAGER.
